UNITED STATES PATENT OFFICE.

BENJAMIN H. MANSKER, OF PINCKNEYVILLE, ILLINOIS.

ROAD GRADER.

Application filed April 23, 1927. Serial No. 186,079.

The device forming the subject matter of this application is a grader intended primarily for use on the highway, and one object of the invention is so to construct the grader blocks and the scraper blades, that both the grading and scraping instrumentalities may yield vertically, and conform to the crown of the highway.

Another object of the invention is to provide novel means whereby the scraper blades and the grader blocks may be tilted forwardly or backwardly, and be held in any positions to which they may have been tilted.

Another object of the invention is to provide novel means for drawing the gangs together, and for holding them in any position to which they may have been adjusted, with respect to each other, transversely of the draft line.

Another object of the invention is to improve the scraper blade so that it will have a double edge for engagement with the roadway, the construction being such that the scraper blade will not tend to jump about.

It is within the province of the disclosure to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawings:—

Figure 1 shows in top plan, a device constructed in accordance with the invention;

Figure 2 is an end elevation disclosing one of the gangs;

Figure 3 is a section taken about on the line 3—3 of Figure 1;

Figure 4 is a section taken about on the line 4—4 of Figure 1.

The device forming the subject matter of this application comprises oppositely disposed gangs 1 and 2. Each gang includes a rear line of grader blocks 3 having their ends overlapped, as shown at 4, pivot elements 5 connecting the overlapped ends 4 of the blocks 3 for vertical swinging movement, so that the rear line of grader blocks 3 can conform to the cross sectional curve, or crown,

of the roadway. A line of intermediate grader blocks 6 are disposed in front of the rear grader blocks 3. The ends of the intermediate grader blocks 6 are overlapped as shown at 7, the overlapped ends 7 of the grader blocks 6 being connected by pivot elements 8 so that the grader blocks 6 can have relative vertical swinging movement and thus conform to the crown of the roadway. The pivot elements 5 and 8 may be bolts, passing through the overlapped ends of the blocks. A line of scraper blades 9 is located in front of the line of intermediate grader blocks 6. The scraper blades 9 are overlapped at their ends, as shown at 10. Spacers 11 are interposed between the overlapped ends of the scraper blades 9. Pivot elements 12 pass through the spacers 11, and through the overlapped ends 10 of the blades 9, and thus the scraper blades 9 are pivotally connected for relative vertical movement, so that they may conform to the shape of the roadway.

Upstanding levers 14 are mounted on the rear grader blocks 3, there being similar levers 15 on the intermediate grader blocks 6. The scraper blades 9 are supplied with upstanding levers 16. The central one of the levers 14 has an upwardly prolonged extension 17 carrying a latch mechanism 18. Upper connecting bars 19 are united by pivot elements 21 with the levers 14, 15 and 16. Lower connecting bars 20 are united by pivot elements 23 with the levers 14, 15 and 16. On the rear end of the central upper connecting bar 19 there is a segment 22 wherewith the latch mechanism 18 cooperates. It is possible to disengage the latch mechanism 18 from the segment 22, and, by means of the lever extension 17, the levers 14, 15, and 16, and the bars 19 and 20, to swing the blocks 3 and 6 and the scraper blades 9 to any desired angle with respect to the vertical. The parts specified may be held in adjusted positions by engaging the latch mechanism 18 with the segment 22. The forward ends of the lower connections 20 are pivotally united by means of links 24 with trees 25 having a plurality of openings 26, in any of which may be mounted a V-shaped draft connection 27. The central bars 19 are connected with the side bars 19, as shown in Figure 1, by diagonal braces 28, the ends of which may be mounted on certain of the pivot elements 21 that connect the levers 14, 15 and 16 with the upper bars 19.

The scraper blades 9 are inclined for-

wardly at their lower edge, to form a wing 29. To the rear surface of each surface blade is attached an angle member 30, one flange 31 of which extends rearwardly at an obtuse angle to the part 29, as shown in Figure 2. The scraper blade thus has a double engagement with the surface of the roadway, the lower edge of the flange 31 and the lower edge of the wing 29 being located in approximately the same horizontal plane.

On the outermost block 6 of the gang 2 there is a pulley 32 over which is rovè a draw member 33, such as a cable or other flexible element, one end of the draw member or cable 33 being connected at 34 to the innermost one of the blocks 6 of the gang 1. The flexible element 33 is wound about a shaft 35 journaled in bearings 36 on the outermost scraper blade 9 of the gang 2, the shaft 35 being journaled in bearings 36 on the outermost one of the scraper blades 9 of the gang 2. The shaft 35 is equipped with a crank 37 of any other suitable means whereby the shaft may be rotated. A flexible connection, such as a chain 38 connects the inner scraper blades 9 of the gangs 1 and 2. A flexible connection, such as a chain 39, is secured at 40, at one end, to the innermost block 3 of the gang 2, and the innermost block 3 of the gang 1 carries a hook 41, or the like, which is pivotally mounted, the hook being adapted to be engaged in any of the links of the chain 39, to vary the length of the chain. By means of the crank 37, the shaft 35 may be rotated, and the flexible element 33 may be employed to pull the gang 1 endwise with respect to the gang 2. When the gangs have been adjusted properly with respect to each other, transversely of the

draft line, the effective length of the chain 39 is adjusted accordingly, by engaging the hook 41 in any of the links of the chain, and the machine, then, will ride in the relation shown in Figure 1, for instance.

What is claimed is:—

1. A grader of the class described, comprising oppositely disposed gangs, a draw member connected to one gang and extended transversely of the draft line to the other gang, means on said other gang for winding up the draw member thereby to pull the gangs toward each other and to dispose the gangs at different angles with respect to the draft line, flexible connections between the front and rear ends of the gangs and located at the inner ends of the gangs, and means for varying the length of one of the connections.

2. A grader of the class described, comprising oppositely disposed gangs, flexible connections between the inner ends of the gangs and located at the forward and rear ends of the gangs, means for varying the length of one of the connections, a winding device at the forward outer corner of one gang, a draw member engaged with the winding device, an anchor connecting the draw member with the inner end of the other gang at a point between the connections, a direction-changing guide on said one gang and located behind the winding device, the draw member being extended from the anchor to the guide, transversely of the draft line, and forwardly from the guide to the winding device.

In testimony that I claim the foregoing as my own, I have hereto affixed my signature.

BENJAMIN H. MANSKER.
